UNITED STATES PATENT OFFICE.

THOMAS F. MORRIN, OF JERSEY CITY, NEW JERSEY; THOMAS F. MORRIN, JR., ADMINISTRATOR OF SAID THOMAS F. MORRIN, DECEASED.

STEAM-BOILER.

No. 847,427.

Specification of Letters Patent.

Patented March 19, 1907.

Application filed May 20, 1903. Serial No. 157,914.

To all whom it may concern:

Be it known that I, THOMAS F. MORRIN, a citizen of the United States, and residing at Jersey City, county of Hudson, and State of New Jersey, have invented certain new and useful Improvements in Steam-Boilers, of which the following is a specification.

My invention relates to steam-boilers, and while it has particular reference to steam-boilers of the water-tube type the invention is not limited thereto.

In the accompanying drawing I have shown several forms of boilers in which my invention is embodied.

15 In Figure I, I have shown a front view, partly in section, of a boiler of the general type now known on the market as the Babcock & Wilcox water-tube boiler. In Fig. II, I have shown a rear view of the said boiler with the walls partly in section. In Fig. III, I have 20 shown a longitudinal sectional view of the boiler of the type shown in Figs. I and II. Fig. IV is a side elevation of a boiler embodying my invention, the said boiler being 25 of the marine type; and Fig. V is an end elevation or detail view of the upper part of the boiler, showing the mode of arranging the feed-water heater and superheater in the boiler.

30 Referring particularly to Fig. II, a represents the drums of the boiler, which drums are ordinarily placed at the highest point in the boiler. The bricked-in portions *b* of the boiler serve to surround the iron-work and 35 tubes, as is usual in stationary boilers. *c* is the fire-box, to which access is obtained by the usual type of door *d*, and at the rear of the fire-box is a bridge-wall *e*. Extending longitudinally of the boiler and suitably supported therein are one or more sets of inclined water-tubes *f*, connected by suitable 40 headers *g*, shown in the present instance as serpentine headers, although the said headers may be of any desired construction. The 45 set of water-tubes communicate by a trunk or series of trunks *h* with the drum at one end and by a trunk or set of trunks *i* at the other end in order to produce the desired and necessary circulation. At or above the bridge- 50 wall *e* is a baffle-plate *j*, shown in the present instance as inclined and apertured for the passage of the water-tubes *f*. Another baffle-plate *k* is or likewise may be provided, the same being preferably located between 55 the second flame-bridge *l* and the bridge *e*.

By thus locating the baffle-plates and fire and flame bridges the course of the flame, gases, and products of combustion is as follows: From the fire-box the flame and products of combustion pass upward in front of the first flame-bridge *e* and the baffle-plate *j*, passing over the upper edge of the baffle-plate *j*, thence downward among the tubes beneath the second baffle-plate to the rear thereof, and thence upward, passing out of the boiler through the flue connection *m*. It will be observed that a space above the longitudinally - extending group of water-tubes is left above the said tubes and in front of the second flame-bridge. This space is lettered *o* in the drawing and is for the purposes of containing the superheater. By referring to Fig. III it will be noticed that this superheater consists of a series of tubes *o'*, united by common headers *o''*, herein shown as serpentine headers.

In Fig. I, I have shown a pipe connection *o''*, by which the steam may enter the superheater, and pipe connections *o'*, by which it may find a means of exit therefrom.

By referring to Fig. III it will be observed that there is a space in the rear of the rear or second flame-bridge *l*, within which I prefer to locate the feed-water heater. The feed-water heater consists of transverse tubes *p*, united by headers *q* in the same manner as in the case of the constituent parts of the superheater. The tubes constituting the feed-water heater are provided with any desirable useful form of pipe-fittings *o''* and *o'''* and the headers are preferably located within the wall of the boiler, so that the flame does not come in contact with the points of junction of the headers and tubes where the tubes are expanded into the headers. At the ends of the feed-water heater I preferably locate and arrange one or more doors *o''* in such manner that upon removing the doors access may be obtained to the feed-water heater for the purpose of cleaning, repairs, and inspection.

Details of the connections of the superheater and feed-water heater or economizer are not given in Figs. I, II, and III, as in Fig. IV and V such connections are fully shown, and consequently have been omitted from Figs. I, II, and III for the purpose of clearness.

The situation of the superheater and the feed-water heater as shown, whereby the superheater is nearest the grate, so that it

shall receive the greatest amount of heat and the steam may be dried as thoroughly as possible, I consider important, and this is the construction preferred by me. I likewise provide a door r in the side of the brick-work, which is similar to the door s , whereby the tubes of the feed-water heater or economizer can readily be made accessible.

Referring now to Figs. IV and V, which, as before stated, show a marine type of boiler, the fire-box grate-bars are indicated by the reference-numeral 1 and the back wall of the fire-box by the reference-numeral 2. Located above the fire-box is a flame wall or bridge 3, herein located with a vertical baffle-plate 4. Above the wall 3 is a series of water-tubes 5, communicating at their ends by a series of headers 6 and 7. These headers are preferably serpentine headers and are provided with trunks. The headers 6 deliver into a suitable header or manifold 8, connecting by pipe or pipes 9 with a steam and water drum 10.

In the drawing I have shown a deflector-plate 11, located inside of the drum 10, opposite the orifice 9^a of the pipe 9. This deflector-plate is useful to deflect the steam and hot water entering the drum through the pipe 9. The lower part of the drum 10 communicates by a suitable trunk or trunks 12 with the header 7, whereby efficient steam circulation is secured. The baffle-plate 4 extends upward from the flame bridge or wall 3, and another baffle-plate 13 extends downward about half-way from the top of the group of inclined water-tubes. A suitable perforated partition or baffle-plate 14 likewise is provided and extends on an incline from the top of the frame of the boiler to the top of the baffle-plate 13.

I have shown in Fig. IV by the arrows the course of the flame and products of combustion. Preferably located in the rear of the inclined baffle-plate is a superheater consisting of headers 15, receiving the ends of tubes 16. These tubes 16 extend transversely of the boiler, preferably at substantially right angles to the inclined water-tubes 5. Steam comes to the superheater from the drum by the pipe 17. Owing to the fact that there is a partition 18 in the header the steam is unable to pass laterally through the header, but is deflected to the tubes 16, crossing the boiler and returning through the other set of tubes 55 to the other side of the header 15, and thence passes out through the pipe 18^a. In the space below the top of the boiler-frame and in front of the baffle-plate I have shown a feed-water heater consisting of a plurality of headers 19, connected by pipes 20, (shown in dotted lines in Fig. V,) extending transversely of the boiler, as in the former cases. The feed-water heater is preferably connected by a pipe 21 to the steam and water drum 10.

Having described my invention, what I

claim, and desire to secure by Letters Patent, is—

1. In a steam-boiler the combination of a group of steam-generating water-tubes, means for effecting circulation, a grate below the tubes and a baffle-plate or flame-bridge extending transversely of the boiler and dividing the boiler into two compartments, a superheater consisting of a series of tubes extending entirely across the path traveled by the products of combustion, in the compartment nearest the grate, and an economizer or feed-water heater composed of tubes similarly arranged in the other compartment, substantially as described. 80

2. In a steam-boiler the combination of a group of steam-generating water-tubes, extending longitudinally of the boiler, means for effecting circulation, a grate below the tubes and a baffle-plate or flame-bridge above the tubes, extending transversely of the boiler and dividing the boiler into two compartments, a superheater consisting of a series of tubes extending entirely across the path traveled by the products of combustion, in the compartment nearest the grate, and an economizer or feed-water heater composed of tubes similarly arranged in the other compartment, substantially as described. 90

3. In a steam-boiler the combination of a group of steam-generating water-tubes f extending longitudinally of the boiler, means for effecting circulation, a grate below the tubes, flame-bridge e , baffle-plate j , a baffle-plate k dividing the boiler into two compartments, transversely-arranged superheating-tubes extending entirely across the path of the heated gases and located above the steam-tubes f , in the compartment nearest the grate, flame-bridge l , and transversely-arranged feed-water-heating tubes extending entirely across the path of the heated gases, and connections for said tubes, substantially as described. 100 105

4. In a steam-boiler the combination of a group of steam-generating water-tubes extending longitudinally of the boiler, means for effecting circulation, a grate below the tubes and a baffle-plate or flame-bridge extending transversely of the boiler and dividing the boiler into two compartments, a superheater in the compartment nearest the grate and an economizer or feed-water heater composed of a series of tubes extending across the path traveled by the products of combustion in the other compartment; said superheater and economizer both being located over the steam-generating water-tubes, substantially as described. 110 115 120 125

5. In a steam-boiler the combination of a group of steam-generating water-tubes, extending longitudinally of the boiler, means for effecting circulation, a grate below the tubes, a flame-bridge adjacent to said grate, and a baffle-plate extending transversely of the boiler. 130

the boiler and dividing the boiler into two compartments, an economizer or feed-water heater composed of a series of horizontal tubes in superimposed parallel groups extending transversely across the path traveled by the products of combustion, located between the headers, all of said tubes being situated above said longitudinal steam-gener- ating water-tubes and in the compartment farthest from the grate, substantially as described.

THOMAS F. MORRIN.
